US00D883953S

(12) **United States Design Patent** (10) Patent No.: **US D883,953 S**
(45) Date of Patent: **** May 12, 2020**

(54) **SOUND BAR**

(71) Applicant: **LG ELECTRONICS INC.**, Seoul (KR)

(72) Inventors: **Yeonui Chong**, Seoul (KR); **Junki Kim**, Seoul (KR); **Sungyong Park**, Seoul (KR); **Sooyoung Park**, Seoul (KR)

(73) Assignee: **LG Electronics Inc.**, Seoul (KR)

(**) Term: **15 Years**

(21) Appl. No.: **35/505,382**

(22) Filed: **Jan. 26, 2018**

(80) **Hague Agreement Data**

Int. Filing Date: **Jan. 26, 2018**

Int. Reg. No.: **DM/099996**

Int. Reg. Date: **Jan. 26, 2018**

Int. Reg. Pub. Date: **Jul. 27, 2018**
